BIRD FEEDER

James R. Waite, 95 Northwoods Road, Manhasset, N.Y.

Filed Dec. 27, 1961, Ser. No. 68,091

Term of patent 14 years

(Cl. D31—2)

FIG. 1.

FIG. 2.

FIG. 3.

FIG. 4.

FIG. 1 is a side perspective view of a bird feeder showing my new design;

FIG. 2 is a top plan view thereof;

FIG. 3 is a side elevational view thereof; and

FIG. 4 is a front perspective view thereof.

The side not shown has substantially the same appearance as the side shown.

I claim:

The ornamental design for a bird feeder, as shown and described.
